UNITED STATES PATENT OFFICE.

HOMER E. CRANDALL, OF SALAMANCA, NEW YORK.

DESIGN FOR A FAN.

SPECIFICATION forming part of Design No. 33,935, dated January 22, 1901.

Application filed December 6, 1900. Serial No. 38,971. Term of patent 3½ years.

To all whom it may concern:

Be it known that I, HOMER E. CRANDALL, a citizen of the United States, residing at Salamanca, in the county of Cattaraugus and State of New York, have produced a new and original Design for a Fan, of which the following is a specification.

This invention relates to a new and original design for a fan; and the essential features reside in the design as illustrated in the accompanying facsimile drawings, wherein—

Figure 1 is a plan view of a fan embodying the features of the design. Fig. 2 is a transverse vertical section of the same.

15 The numeral 1 designates a circular flat body having a pan contour 2 therein and in-

cluding the representation of a spout 3 and handle 4. The pan contour is in the central portion of the body 1, and within the confines of said contour on one side is the representation of a buffalo.

Having thus described the invention, what is claimed as new is—

The design for a fan, as herein shown and described.

20 In testimony that I claim the foregoing as my own I have hereto affixed my signature in the presence of two witnesses.

HOMER E. CRANDALL.

25 Witnesses:

W. H. HAZARD,
F. A. RHODES.
